(57) **CLAIM**

The ornamental design for a multi-function layout square with laser, level and compass, as shown and described.

DESCRIPTION

FIG. 1 is a perspective view of a first embodiment of a multi-function layout square with laser, level and compass showing my new design from the top, front end, and one side;

FIG. 2 is a perspective view thereof, shown from the bottom, back end, and side opposite that shown in FIG. 1;

FIG. 3 is a perspective view of a second embodiment of the multi-function layout square with laser, level and compass showing my new design from the top, front end, and one side;

FIG. 4 is a perspective view thereof, shown from the bottom, back end, and side opposite that shown in FIG. 3;

FIG. 5 is a perspective view of a third embodiment of the multi-function layout square with laser, level and compass showing my new design from the top, front end, and one side;

FIG. 6 is a perspective view thereof, shown from the bottom, back end, and side opposite that shown in FIG. 5;

FIG. 7 is a perspective view of a fourth embodiment of the multi-function layout square with laser, level and compass showing my new design from the top, front end, and one side; and,

FIG. 8 is a perspective view thereof, shown from the bottom, back end, and side opposite that shown in FIG. 7.
